UNITED STATES PATENT OFFICE

2,592,486

HYDRAULIC METERING FUSE

Donald A. Stark, Chicago, Ill., assignor to
William Waterman, Chicago, Ill.

Application July 10, 1945, Serial No. 604,215

13 Claims. (Cl. 137—153)

1

This invention relates to so-called fuses for altering or interrupting fluid flow, and particularly to metering fuses designed to operate after a predetermined volume of flow. Among other objects, the invention aims to provide means for increasing the metering range of the fuse and particularly for adapting fuses to meter low rates of flow.

The nature of the invention and other objects and advantages thereof may be readily understood by reference to illustrative fuses adapted for metering low rates of flow and shown in the accompanying drawings.

In said drawings:

Fig. 1 is a longitudinal section of a fuse;
Fig. 2 is a cross section taken on the plane 2—2 of Fig. 1;
Fig. 3 is a cross section taken on the plane 3—3 of Fig. 1 and showing the broken plane 4—4 on which Fig. 1 was taken; and

Fig. 4 is a longitudinal section of a different form of fuse embodying the present invention.

For purposes of illustration the invention is here shown applied to two different types of metering fuses disclosed respectively in Waterman application Serial 525,275, now Patent 2,512,190, and Waterman Patent 2,354,161. But it will be apparent that the principle of the invention is not limited to these types of fuses.

In fuses of the type to which the invention is shown applied, the fuse valve operates to alter the fluid flow (in this case cut off the flow) after a predetermined volume of flow has passed through the line regardless of the pressures involved, and in this instance also regardless of the variation in viscosity of the fluid. As soon as flow starts a valve element starts to move toward its seat which it reaches after a predetermined volume of flow. Fuses of this type protect against excessive loss of fluid in the event of line breakage; they permit such volume of fluid to flow (preferably a slight additional amount as a safety factor) as is required to operate a particular instrumentality, such as a piston, and close the line (to prevent further loss) if the flow exceeds this amount, as would be the case under abnormal situations, such as fracture of the line or excessive leakage from whatever cause.

It has heretofore been necessary to render the fuse insensitive to all closing forces except only the force of fluid flow. Otherwise extraneous forces such as vibration, inertia, and gravity might cause closing of the line. Inertia forces are particularly severe in aircraft; sudden changes in direction, such as pulling out of a dive, can easily increase gravity and inertia forces to many times

2

gravity. Restraining means such as friction or a spring (e. g. spring 38 in Waterman Patent 2,354,161) have been employed to resist closing of the fuse valve by such extraneous forces, but obviously such restraining means render the fuse insensitive to low flow (such as might be caused by a small fracture or leak in the line) which exerts a force insufficient to overcome the restraining means. The fuse therefore is insensitive to low flow whether it results from leakage or is an incident to normal operation.

While it is possible for a given rate of flow (even though it be small) to design a fuse so that the force of flow will be sufficient to operate the fuse against a spring or other restraint, such design could not be employed for other rates of flow, and it is of the utmost practical importance that a single design be applicable to a wide range of flow rates.

According to the present invention a fuse valve is unbiased and free to respond to flow however small, yet it is held against a closing movement by other forces such as inertia, gravity, vibration, etc. This result is obtained as presently explained in detail by holding the fuse valve against movement toward its seat by a device itself releasable only by flow and insensitive to other forces.

In the fuse illustrated in Fig. 1, being the type shown in said Waterman application, the fuse valve 10 is moved toward its seat 11 by small pressure drop in the fuse caused by the major flow which passes around the valve and which induces a relatively small auxiliary or divided flow to move the valve. The rate of such auxiliary flow determines the closing or metering of the fuse thereby imposing substantially no restriction on the main flow. As more fully described in said Waterman application, the valve 10 in the form of a piston operates in a sleeve or cylinder 12 mounted inside the larger fuse housing 13 leaving a substantial space 14 around the cylinder 12 through which the main flow passes.

Flow enters the fuse housing 13 through a standard threaded coupling element 15 which itself is threaded into the housing and sealed thereto by a sealing ring 16. The opposite end of the housing is provided with a similar standard coupling element 17, in this case integral with the housing. Flow entering passage 18 is deflected laterally through passages 19 in the head 20 to the main passage 14 around the valve and re-enters the central space 21 of the fuse through control holes 22 in advance of the valve seat 11, so that seating of valve 10 would cut off flow. A minor portion of the flow, i. e. the so-called

auxiliary stream, passes through control orifice 23 (which it reaches through passages 24 in head 20) and acts on piston 25 with which the valve 10 is incorporated. Control holes 22 and the passage 14 are designed, as explained more fully in said Waterman application, to provide a slight pressure drop in reaching the passage 21, which pressure drop induces the flow through control orifice 23. The latter is adjustable, as presently explained, and its size determines the speed of advance of piston 25 and valve 10 towards its seat and therefore the volume of flow passing through the fuse before the valve seats and interrupts further flow. As further explained in said Waterman application, it is possible by proper design of such control holes 22, passage 14, and control orifice 23, to obtain a substantially constant ratio of flow between the main and auxiliary streams regardless of variation of viscosity, so that the metering action of the fuse is not affected by such variation in viscosity. This is particularly important for oils, but relatively less important where the temperature is reasonably constant or the fluid is a light liquid or gas where the change in viscosity can be ignored.

In the present fuse the spring which operated to prevent advance of valve 10 by extraneous forces other than flow, has been replaced by a device which in this case is flow responsive and which prevents advance of piston 25 and valve 10. Such device is here shown in the form of a piston 26 which blocks passage 21 to free escape of the fluid from the fuse. An extension 27 on piston 26 bears against the end of valve 10 and holds it against movement toward its seat unless and until piston 26 is moved. The latter is held against piston 25 by a spring 28 which is strong enough to prevent movement of valve 10 against extraneous forces but which nevertheless because of the substantial area of piston 26 readily yields under a very low pressure drop created when fluid starts to flow through the housing. For convenience, this pressure drop is referred in the claims as fluid pressure. In practice valve 10 and its piston 25 are very light in weight and spring 28 need be precompressed to exert a force only about four or five times the weight of the valve and its piston.

Except where rendered insensitive to predetermined minimum flow as later explained, any flow however light is therefore sufficient to move piston 26 against compression of its spring and thereby release valve 10 so that it responds at once to flow. When piston 26 and its extension 27 have been moved sufficiently to clear cylinder 12, it uncovers ports 29 in cylinder 30. Thus flow may pass out of the fuse through ports 29 and the passage 31 surrounding cylinder 30 from which passage fluid reaches the exit passage 32 through radial passages 33 in the head 34. Cylinder 30 is sealed inside housing 13 by the sealing ring 13' which prevents short circuiting of the fluid.

Upon interruption of flow, spring 28 returns piston 26 and valve 10 to initial position, but return flow may nevertheless freely traverse the fuse through the check valve 35 which in this instance is carried in the head of piston 26 and inside the projection 27. A spring 36 seats the valve 35 on its seat 37 but readily yields on return flow to permit fluid to reach control holes 22 through ports 38.

Control orifice 23 is advantageously designed to embody a check valve which permits free

escape of fluids inside piston 25 (when the latter returns) so as not to restrict return of the latter as would be the case if return flow were obliged to pass through orifice 23. As shown particularly in Figs. 1 and 2 the orifice 23 is in the form of a movable disc which on forward flow rests on the edge 40 of the central passage 41 in the orifice fitting 42. Return flow through passage 41 raises orifice 23 from its seat and escapes through the space 43 underneath the orifice. The latter is limited in its movement by a surrounding cylinder 44 having a central bore 45 extending only partly through the cylinder and providing a space for the orifice disc 23 and the projecting tip 46 of the orifice fitting 42. Auxiliary bores 47 passing through the cylinder 44 communicating with the space 43 permit escape of the fluid to the central space 48 with which the radial passages 24 connect. The central bore 45 is counterbored at 49 to provide a space above the orifice through which return fluid passing through the orifice may escape into the auxiliary bores 47. The orifice fitting and cylinder 44 are enclosed by housing 50 having a shoulder 51 against which cylinder 44 seats. A spring ring 52 holds the fitting in place and a sealing ring 53 prevents leakage around the orifice and its fitting.

The orifice housing 50 is advantageously made longitudinally adjustable relative to the head 20 for which purpose it is provided with a screw threaded tip 54 screwed into head 20. It is also provided with an extension 55 adapted to engage the inner face of valve piston 25 and limit its return movement. By this means relatively fine metering adjustments may be made. Obviously the return position of valve 10 determines the volume metered by the fuse. The threaded tip 54 is advantageously provided with a tool receiving recess in the form of a screwdriver slot 56 by means of which such adjustments may be made while the fuse is completely assembled.

Major changes in the metering capacity of the fuse are advantageously made by varying the size of the orifice 23. This is effectively accomplished by employing orifice plates with orifices 23 of varying sizes which may be substituted one for the other. The fine adjustments are made by means of the threaded tip 54 as explained above. The friction and sealing ring 57 of synthetic rubber or the like is located in the angular space outside the adjusting housing 55 and inside the cylindrical extension 58 on head 20. This seal prevents leakage between the head and housing 55 and also prevents relative rotation between the two which might disturb the adjustment of the fuse.

Return flow through orifice 23 advantageously serves to wash out the orifice and to remove any particles of solid matter which might alter the metering adjustment. Such particles escape into the bores 47 from the communicating counterbore 49.

In assembling the fuse the parts are successively introduced into housing 13 from the end from which coupling element 15 has been removed. A bearing washer 59 having a chamfered interior 60 to permit free access to passages 19, and a spring washer 61 are located between the head 20 and the shoulder 62 inside coupling 15. The spring washer insures adequate pressure to hold the assembled elements in engagement with each other inside the fuse without the necessity of impractically close tolerances which would otherwise be necessary to

permit the coupling element to seat against the end 63 of the housing 13 and at the same time transmit the necessary pressure to the elements inside the housing.

In Fig. 4 is illustrated the adaptation of the present invention to a fuse of the type shown in Waterman Patent 2,354,161. As here shown the valve 70 which corresponds to the valve 40 of said patent is held against movement by a piston 71 which blocks escape of fluid from the fuse and prevents movement of said valve by reason of engagement of the piston extension 72 therewith until piston 71 is moved by fluid flow clear of the valve seat 73. In the latter position it uncovers ports 74 through which flow may reach the exit orifice 75 of the fuse 76.

As here shown the cylindrical extension 77 carried by the brake cylinder 78 fits inside and bears against a reduced cylindrical portion 79 of the fuse housing 80. Flow entering the passage 81 enters the angular passage 82 around the brake cylinder through passages 83 in the end of the brake cylinder. Passage 82 leads through ports 84 to the interior space 85 wherein the flow operates on valve 70 as explained in said Waterman patent. The brake or dashpot piston 86 retards movement of valve 70 so as to affect a metering action described in said Waterman patent.

As explained above in connection with the form of fuse shown in Fig. 1, the piston valve 71 readily advances and opens ports 74 under fluid pressure against spring 87 without involving a substantial pressure drop.

Return flow opens check valve 88 as previously explained in connection with the form of fuse shown in Fig. 1 and acts on valve 70 to return the same to initial position. In this case fluid enters brake cylinder 78 through check valve 89 which on forward travel is closed and obliges fluid to escape only through the metering orifice 90.

The metering orifice is contained in a replaceable orifice fitting 91 which is held in place by the annular set screw 92.

The several elements inside the fuse housing are introduced therein on assembly through the end carrying the removable coupling element 93. An annular clamping screw 94 bears against the end of the brake cylinder and presses it against the cylinder 95 carrying piston 71. A seal 96 prevents by-passing of fluid around piston 71.

If desired, both types of fuse may be made insensitive to operation by any predetermined minimum rate of flow. For example, if the system involve normal leakage past pistons, etc., such flow as is represented by the leakage may be permitted to pass the fuse without inducing operation. Also, the fuse may be made to operate only when the flow exceeds a predetermined rate. The fuse may be given the aforesaid functions by providing a control port, in this case the port 97 in valves 85 and 88, whose size is designed to permit the aforesaid limited flow without involving operation of the fuse. Thus flow may bypass pistons 26 and 71 without inducing operation until it exceeds the predetermined value in which case these pistons will be operated as above described. In the event the viscosity of the fluid varies considerably it is preferable that the orifice 91 be given a sharp edge to minimize the effect of variation in viscosity.

Springs 28 and 87 in the respective illustrative fuses may without harm be much stronger than

necessary merely to counteract gravity, inertia, etc., since only a slight additional pressure drop would be involved. In fuses where there is no return flow (which is utilized to return the valves to initial position) these springs may be used to return the valves and for that purpose may advantageously be made stronger for a quicker return. The volume displaced by the returning valve is so small that if there be no orifice 97 in the check valves the necessary small volume of return flow for this purpose will readily be drawn into the housing by leakage past the piston valve 26 or 71.

Obviously the invention is not limited to the details of the illustrative fuses nor to the specific type of fuses here shown. Moreover it is not indispensable that all features of the invention be used conjointly since various features may be used to advantage in different combinations and subcombinations.

Having described my invention, I claim:

1. In a fuse of the character described, the combination comprising a housing adapted to be incorporated in a fluid line, a valve seat in said housing, a normally open valve exposed to and adapted to be moved by fluid flow toward said seat, said housing having a discharge orifice, an orifice closure responsive to fluid pressure in said housing for opening said orifice, said closure having a device holding said valve against closing movement and movable with said closure on opening of said orifice to permit said valve to move.

2. In a fuse of the character described, the combination comprising a housing adapted to be incorporated in a fluid line, a valve seat in said housing, a normally open valve in said housing exposed to and adapted to be moved by fluid flow toward said seat, said housing having a discharge orifice, a spring pressed piston closing said orifice and yieldable in response to fluid pressure in said housing to open said orifice to permit flow through said housing and a device carried by said piston and engaging said valve to hold the latter open, said device being movable with said piston to release said valve upon opening of said orifice.

3. In a fuse of the character described, the combination comprising a housing adapted to be incorporated in a fluid line, a valve seat in said housing, a normally open valve in said housing exposed to fluid flow and adapted to be moved toward said seat in response to fluid flow, said housing having a discharge orifice through which fluid flow passes, an orifice closure normally closing said orifice during periods of absence of fluid flow and adapted in said normally closed position to prevent movement of said valve in response to fluid flow, said closure being movable in response to fluid pressure to open said orifice and thereby to permit said valve to move, and a check valve in said housing to permit return flow to pass said closure.

4. A fuse of the character described, comprising in combination a housing having a fluid passage and valve seat therein, a normally open valve exposed to fluid flow and movable toward said seat in response to fluid flow through said housing to close said housing against further flow after a predetermined volume of flow, said housing having a discharge orifice through which said flow passes, a piston closing said orifice during periods of no flow and yieldable in response to fluid pressure to open said orifice to permit flow through the housing, said piston having an extension

thereon engaging said valve while said piston is in closed position to prevent movement of said valve under forces of gravity and inertia.

5. A fuse of the character described comprising in combination a housing having a longitudinal passage thereto and adapted to be connected in a fluid line, a cylinder in said housing and spaced therefrom to provide fluid passages around said cylinder, a valve seat in said housing, a piston valve slidable in said cylinder and exposed to fluid flow and movable in response to fluid flow toward said seat to cut off flow through said housing, said housing having a discharge orifice therein, a closure in said housing adapted to block said orifice, a spring biasing said closure to block said orifice during periods of no flow, an extension carried by said closure and engaging said valve to hold the same open against forces of gravity and inertia, said closure being yieldable under flow pressure to open said orifice and move said extension out of engagement with said valve, and a check valve in said closure to permit return flow to pass through said housing without moving said closure.

6. A fuse of the character described comprising in combination a housing having a longitudinal passage thereto and adapted to be connected in a fluid line, a cylinder in said housing and spaced therefrom to provide fluid passages around said cylinder, a valve seat in said housing, a piston valve slidable in said cylinder and exposed to fluid flow and movable in response to fluid flow toward said seat to cut off flow through said housing, said housing having a discharge orifice therein, a closure in said housing adapted to block said orifice, a spring biasing said closure to block said orifice during periods of no flow, and an extension carried by said closure and engaging said valve to hold the same open against forces of gravity and inertia, said closure being yieldable under fluid pressure to open said orifice and move said extension out of engagement with said valve.

7. A metering device of the character described comprising in combination a housing adapted to be incorporated in a fluid line, a cylinder in said housing and spaced therefrom to provide passages around the cylinder for fluid flow, a valve seat in said housing, means including a piston valve in said housing and movable in response to fluid flow toward said seat to cut off flow after a predetermined volume of flow, and a device longitudinally adjustable relative to said cylinder to engage the piston valve in its open position to adjust the length of stroke of said piston valve and thereby to vary the volume metered.

8. In a fuse of the character described, the combination comprising a housing adapted to be incorporated in a fluid line, a valve seat in said housing, a normally open valve in said housing exposed to and adapted to be moved by fluid flow toward said seat, said housing having a discharge orifice, a spring pressed piston closing said orifice and yieldable in response to predetermined fluid pressure to open said orifice and thereby to permit said valve to close under the pressure of fluid flow, and a device carried by said piston and engaging said valve to hold the latter open, said device being movable with said piston to release said valve upon opening of said orifice, said piston having therein a passage of predetermined size to permit a predetermined flow through said housing before development of sufficient fluid pressure on said piston to move the same, said piston being adapted to move to open

7
said orifice when the flow through said passage exceeds a predetermined maximum.

9. In a fuse of the character described, the combination comprising a housing adapted to be incorporated in a fluid line, a valve seat in said housing, a normally open valve in said housing exposed to fluid flow and adapted to be moved toward said seat in response to fluid flow, said housing having a discharge orifice through which fluid flow passes, an orifice closure normally closing said orifice and thereby preventing closing movement of said valve, said closure being movable in response to a predetermined pressure of fluid to open said orifice and thereby to permit said valve to move, said orifice closure having therein a passage to permit limited flow through said housing, and means for resiliently holding said closure in closed position and adapted to yield under the force of fluid pressure existing when the flow through said passage exceeds a predetermined maximum.

10. In a fuse of the character described the combination with a fluid pressure line of a housing having therein a valve seat, a normally open valve adapted to be set in retracted open position and moved by the force from the flow of fluid from said retracted position toward its seat to interrupt fluid flow, a device exposed to fluid pressure and sensitive to pressure differences incident to the flow of fluid for holding said valve against movement toward its seat under extraneous forces during periods of interruption of fluid flow, said device moving under the pressure incident to resumption of fluid flow to release said valve to permit the same to move toward its seat under the force of fluid flow, said device having check means releasable on reverse flow to allow return of said valve to retracted position by said reverse flow.

11. In a metering device of the character described, the combination comprising a housing adapted to be associated with a fluid line, a valve seat in said housing, a piston valve slidable said housing toward said seat and arranged to be set in retracted open position, metering means for displacing said piston valve toward said seat at a rate corresponding to the rate of fluid flow in said line, the length of travel of said piston valve toward said seat determining the volume of flow in said line before seating of said valve, and an adjustable stop in said housing for adjusting the limit of the retracted position of said piston for varying the volume metered before seating of said valve.

12. A metering device of the character described comprising in combination a housing adapted to be incorporated in a fluid line, a valve seat in said housing, a piston and valve in said housing slidable from a normally retracted position toward said seat, metering means for displacing said piston toward said seat at a rate corresponding to the rate of fluid flow through said housing to cut off flow after a predetermined volume of flow has passed through the housing, and adjustable screw means adapted to engage said piston and valve in its retracted position to vary the length of stroke of said piston thereby to vary the volume metered before closing of said valve.

13. In a fuse of the character described the combination with a fluid pressure line of a housing having therein a valve seat, a normally open valve adapted to be moved by the force of the flow of fluid toward its seat to interrupt fluid flow, a light weight check piston engaging said

valve during periods of interruption of flow to hold said valve against movement toward closing position under forces other than those of fluid flow, a light spring for holding said check piston in its valve engaging position against forces other than fluid flow, said spring being readily yieldable under low fluid pressure differences against said check piston incident to resumption of fluid flow to release said valve to move toward said seat.
